F. P. KOBERT.

GUY ANCHOR.

APPLICATION FILED SEPT. 30, 1912.

1,111,964.

Patented Sept. 29, 1914.

UNITED STATES PATENT OFFICE.

FRANK P. KOBERT, OF FAIRHAVEN, CONNECTICUT, ASSIGNOR TO THE BARNES & KOBERT MANUFACTURING COMPANY, OF NEW HAVEN, CONNECTICUT, A CORPORATION OF CONNECTICUT.

GUY-ANCHOR.

1,111,964.

Specification of Letters Patent. Patented Sept. 29, 1914.

Application filed September 30, 1912. Serial No. 723,029.

To all whom it may concern:

Be it known that I, FRANK P. KOBERT, a citizen of the United States, and residing at Fairhaven, in the county of New Haven and State of Connecticut, have invented certain new and useful Improvements in Guy-Anchors, of which the following is a specification, such as will enable those skilled in the art to which it applies to make and use the same.

This invention relates to guy anchors for telegraph, telephone or similar poles, and the object thereof is to provide an improved device of this class having a plurality of fluke members one or more of which may be used according to the retaining power desired; a further object being to provide an improved anchor of the class specified which may be used not only as a pole anchor, but as an anchor for smoke stacks and in various other relations in which anchors of this class are required.

The invention is fully disclosed in the following specification of which the accompanying drawing forms a part, in which the separate parts of my invention are designated by suitable reference characters in each of the views, and in which;

Figure 1 is a view showing one use of my improved anchor;—Fig. 2 a bottom plan view thereof or of the head thereof and showing four of the fluke members employed;—Fig. 3 a view similar to Fig. 2, but showing three of the fluke members employed;—Fig. 4 a view similar to Fig. 3, but showing only two of said fluke members;—Fig. 5 a view similar to Fig. 4, but showing the method of employing but one of said fluke members;—Fig. 6 a section on the line 6—6 of Fig. 4, and; Fig. 7 a perspective view of one of the fluke members detached.

In the drawing forming part of this specification, I have shown in Fig. 1 a telegraph or similar pole *a* provided with my improved guy anchor *b*.

The guy anchor *b* comprises an anchor bar or rod *c* having an anchor head *d* at one end and a ring, eye or loop *c*² at the other end with which is connected a guy rope or cable *e* which is connected with the pole *a* in the usual manner.

The head *d* may consist of a single fluke member *d*², as shown in Fig. 5, or of two

of said fluke members as shown in Fig. 4, or of three of said fluke members as shown in Fig. 3, or of four of said fluke members as shown in Fig. 2.

The fluke members *d*² consist of plates stamped from sheet metal and approximately triangular in form and having heads *d*³ at one corner, said heads being preferably semi circular in form, and the heads *d*³ are provided with central apertures *d*⁴, and one end of the bar *c* is screw threaded as shown at *c*⁵, and provided with two nuts *f* and *f*² and a washer *f*³. The fluke members *d*² are also provided centrally with other apertures *d*⁵ similar to the apertures *d*⁴ and said fluke members are also preferably provided adjacent to the opposite side edges and on one side thereof with radial ribs *d*⁶ and corresponding radial grooves *d*⁷ in the opposite side face thereof, this construction being designed to give strength to said fluke members which are stamped from sheet metal, as hereinbefore described. When it is desired to use but one of the fluke members the threaded end *c*⁵ of the bar *c* is passed through the central aperture in said fluke member, as shown in Fig. 5, and the nuts *f* and *f*² and washer *f*³ manipulated so as to securely bind said fluke member in position, the washer *f*³ being on the top surface of the head thereof. When it is desired to use two of the fluke members *d*² as shown in Fig. 4, they are placed together with the heads thereof overlapping and the threaded end of the bar *c* passed therethrough, and the nuts *f* and *f*² and washer *f*³ used, as shown in Fig. 2 and as above described, and the fluke members project in opposite directions. In the same manner three of said fluke members may be used, as shown in Fig. 3, or four as shown in Fig. 4, and in the construction shown, the fluke members are of such shape that four of them form an anchor head which is circular in form, three of them an anchor head equivalent to three fourths of a circle in form and two of them an anchor head equivalent to one half of a circle in form. When the separate fluke members are placed together, as shown in Figs. 2 and 3, the side flanges *d*⁸, formed by the ribs *d*⁶ and *d*⁷, overlap, and said ribs prevent any lateral movement of said fluke members when they

are securely bound together. The fluke members d^2 or the heads thereof are also, preferably slightly curved, as shown in Fig. 3, so as to make the anchor head or the separate parts thereof concave in cross section, but this feature is not absolutely necessary and may or may not be employed.

It will be understood that the fluke members d^2 may be made of any desired radial dimensions and the size or capacity of the anchor head may thus be increased or decreased, as may be desired, and it will also be understood that the exact form of the said fluke members, as herein shown and described, is not essential the only object in this connection being to provide an anchor of the class specified the head of which consists of a number of parts 1, 2, 3 or more of which may be combined in the manner shown and described so as to provide an anchor of greater or less efficiency, as may be desired.

Having fully described my invention,

what I claim as new and desire to secure by Letters Patent, is;—

In an anchor, an anchor bar provided with a head, consisting of a plurality of fluke members, said fluke members being stamped from sheet metal and being substantially triangular in form and being provided at one corner with semi-circular heads having central apertures through which the anchor bar is passed, and the body portions of said fluke members being provided adjacent to their opposite side edges with radial ribs on the top surface thereof and corresponding radial grooves on the bottom surface thereof.

In testimony that I claim the foregoing as my invention I have signed my name in presence of the subscribing witnesses this 27th day of September 1912.

FRANK P. KOBERT.
